UNITED STATES PATENT OFFICE.

EDWIN DOUGLAS BOYCE, OF NORRISTOWN, PENNSYLVANIA.

TOOL GUARD.

Application filed February 20, 1925. Serial No. 10,561.

My invention consists in a tool guard and more especially in a saw guard having for one of its objects to provide a simple, inexpensive, effective and easily operating safety device adapted more especially for use upon circular saws.

My device is further adapted to cover a circular saw when not in use and to clear the peripheral cutting edge thereof when the work is being fed to the saw or when the saw is being drawn or swung through the work, without interfering with the cutting efficiency of the saw.

It will be apparent that the guard or guards slide upon the work while the saw is free to cut through the work and that they are also adapted to slide upon the work when it is found necessary for the saw to retrace its cut.

I have illustrated my device as used on a woodworking machine with the saw mounted on a single sliding rod but it will be understood that I do not limit my device to this especial use as it may be used upon a stationary saw or upon one adapted to be swung through the work.

It is apparent from the drawings that my device consists of two leaf members and that these may operate independently as for example:—when the saw is tilted for a bevel cut through the work.

Referring to the drawings Fig. 1 is a plan view of my device as attached to the cross-head of a single rod woodworker; Fig. 2 is a side view of my device; Fig. 3 shows the upper stationary guard to which my leaf members are attached; Fig. 4 is a cross-section taken on the line 4—4 of Fig. 2; Fig. 5 is a cross-section on the line 5—5 of Fig. 2; Fig. 6 is a cross-section on line 6—6 of Fig. 2.

Referring more particularly to the drawings 1 denotes the single rod of a woodworking machine, 2 is a collar rigidly secured thereto having graduations thereon adapted to register with graduations scribed on the collar 3 which is an integral part of the cross-head 4, which is provided with the handle 5. A mandrel 6 carries a circular saw 7 at one end and a pulley 8 at the other. An upper stationary guard 9 covers the top of the circular saw 7, this guard is attached to the cross-head 4 by means of screws 10 countersunk in the guard 9. To the guard

9 is attached a reinforced lug 11 by means 55 of screws 12, and countersunk in this lug is a pintle 13 having a nut 14. Mounted upon this pintle are two leaf guards 15 and 16 which are provided with stop lugs 17 and 18 which in turn are provided with set 60 screws 19 and 20 adapted to regulate and determine the downward swing of said leaf guards.

It will be seen that each leaf guard is cut away to allow for the mandrel as shown in 65 the dotted position illustrated in Fig. 2.

In operation the leaf guards will ride upon the work and may assume the extreme position shown by the dotted lines in Fig. 2 and when the work is removed or the saw has 70 passed beyond the work the leaf guards will assume by gravity the normal position shown in Fig. 2. The leaf guards it will be noted simulate the rockers of a sled and will slide upon the work either going or 75 coming.

Having thus described and pointed out the novel construction, combination and arrangement of my parts, what I wish to claim and secure by Letters-Patent is:— 80

I claim:

1. In a saw guard for a reciprocatory saw, the combination of a cover plate mounted in fixed relation to the saw and provided with a lug positioned in advance of the saw; 85 and two cover plates pivotally mounted on said lug and provided with arcuate lower edges.

2. In a saw guard for a reciprocatory saw, the combination of a cover plate mounted in fixed relation to the saw; and two cover plates pivotally mounted on said fixed cover plate in advance of the saw, and provided with arcuate lower edges. 90

3. In a saw guard for a reciprocatory saw, the combination of a cover plate mounted in fixed relation to the saw; two cover plates pivotally mounted on said fixed cover plate in advance of the saw; a stud on each of said pivoted cover plates; and an adjusting 100 screw in each stud adapted to co-act with the fixed cover plate to limit the movement of the pivoted plate upon which the stud is mounted.

In testimony that I claim the foregoing 105 as my own, I affix my signature.

EDWIN DOUGLAS BOYCE.
